A DISPENSING CAP FOR JARS OR THE LIKE

Arnold H. Marler, 8 Wendell Ave., Toronto,
Ontario, Canada

Filed Jan. 15, 1962, Ser. No. 68,317

Term of patent 14 years

(Cl. D58—26)

FIG. 2

FIG. 1 is a top perspective view of a dispensing cap for jars or the like, embodying my new design; and

FIG. 2 is a bottom perspective view thereof showing the other side.

I claim:

The ornamental design for a dispensing cap for jars or the like, substantially as shown.
